UNITED STATES PATENT OFFICE.

ODER C. PENDLETON, OF OKMULGEE, OKLAHOMA.

STEAM HAT-BLOCKING MACHINE.

1,102,542.

Specification of Letters Patent.

Patented July 7, 1914.

Application filed December 18, 1913. Serial No. 807,437.

To all whom it may concern:

Be it known that I, ODER C. PENDLETON, a citizen of the United States, residing at Okmulgee, in the county of Okmulgee and State of Oklahoma, have invented certain new and useful Improvements in Steam Hat-Blocking Machines, of which the following is a specification.

This invention relates to improvements in apparel apparatus and more specifically to steam hat blocking machines.

The object of my invention is to provide a novel hat blocking machine to be heated by a comparatively dry steam, means for creating such steam being provided, and the said steam to be used as well for heating tollipers and other devices used in blocking hats.

My device is to be simple in construction and operation, compact, and adjustable to all hat sizes.

The penetration of steam through the felt of a hat raises the nap thereof and gives to the hat a new appearance.

Other objects of this invention, not at this time more particularly enumerated, will be clearly understood from the detailed description and drawings forming a part of this specification.

With the above and other objects in view, my invention consists in the combination, arrangement, and details of construction disclosed in the drawings and specification, and then, more particularly pointed out in the appended claim.

Referring further to the drawings which form a part of this specification, Figure 1 is a front elevation of my device, while Fig. 2 is a longitudinal side elevation of the superheating box thereof, with a part of the box broken away. Fig. 3 is a cross-sectional view of the hat block and flange.

Referring further to the drawings which are merely illustrative of my invention and wherein similar reference characters designate similar parts throughout the respective views, 1 designates a hollow metallic hat block provided with perforations 1^a and slidably mounted within a hollow metallic flange 2, provided with perforations 2^a, the height of said block above the flange being regulated by a lift 3 secured around steam inlet 4 to which said block is removably mounted, the said block being raised by lever-catches 5, said catches also holding the block in the desired position. By lifting the

hat block by means of said lever-catches one avoids the necessity for taking hold of the steam inlet pipe 4 which is ordinarily hot. The steam inlet pipe 4 is provided with a plurality of universal joints 6 to permit of easy adjustment to varying positions. The flange is also removably mounted to steam inlet 7, both of which said inlet pipes are connected to steam feed pipe 8 which is secured to superheating box 9 provided underneath with a gas burner 10, and preferably mounted on a suitable support 11 conveniently located upon main support or table 12 upon which all of the aforementioned parts are mounted. Projecting from said superheating box 9 is a second outlet pipe 13 to which is secured a flexible tube 14 to which may be attached various kinds of hat blocking irons to be used in a heated condition. A drip-pipe 15 carries off water which may condense in the superheating box. A feed pipe 16 leading to said superheating box carries steam from a separator 17 provided to free the steam from as much of the heavier moisture as possible before passing it into the superheating box where it is vaporized to a still higher degree. The drip pipe 18 carries off condensed steam from the separator and deposits it in a bucket 19 conveniently located to receive all waste water. The separator is also provided with a steam gage 20 which will indicate the steam pressure at all times. Steam is generated preferably by a gas heated boiler 21 provided with the customary burner, 22, water gage 23, and safety-valve 24, though other styles of boiler might serve as well. An electrically operated pump 25 is conveniently located near the boiler for supplying the water therefor, though a hand power or water pressure pump would serve as well.

Having now described and pointed out the new and useful features of my invention, I do not limit myself to the shape of certain parts where the shape is not essential, nor do I restrict myself to the exact details of construction shown and described, but mean and intend to claim all equivalents and variations thereof not departing in principle from my invention and falling within the purview of the appended claim.

What I claim as my invention and desire to secure by Letters Patent is:

In combination a perforate hat-block, a bottom closing said perforate block, a hollow flange extending around said block, a

table upon which said block is mounted, a steam-conveying pipe connected to the bottom of said hat-block, a plurality of stops carried by said steam-conveying pipe, means whereby said pipe is adjustable, releasable props engageable with said stops to adjustably support said hat block, a pipe connected to said flange, and a unitary source

of fluid supply communicating with said first and second-mentioned pipes.

In testimony whereof I affix my signature in presence of two witnesses.

ODER C. PENDLETON.
